UNITED STATES PATENT OFFICE.

OBERLIN SMITH, OF BRIDGETON, NEW JERSEY.

DESIGN FOR A GAGE.

SPECIFICATION forming part of Design No. 25,719, dated June 30, 1896.

Application filed March 16, 1896. Serial No. 583,473. Term of patent 14 years.

To all whom it may concern:

Be it known that I, OBERLIN SMITH, a citizen of the United States, residing at Bridgeton, in the county of Cumberland and State of New Jersey, have invented and produced a new and original Design for Gages, of which the following is a specification.

My invention relates to a design for wire-gages.

10 The leading feature of my design is a body of elliptical form or contour and subsidiary features or notches of gradually-varying sizes and their disposition in such periphery so that the notches of the smallest sizes are arranged 15 in a group at one end of the elliptical body.

This form of gage embraces, among other advantages, those of general beauty and convenient shape for use as a pocket implement.

Referring to the accompanying drawing, B represents the elliptical border of the body C. 20 The numerals "1" to "21," inclusive, represent the larger series of notches of gradually-decreasing size, and those from "22" to "38," inclusive, the smaller series of gradually-decreasing notches, which, it will be observed, 25 are grouped at one end of the periphery of the elliptical body.

What I claim is—

The design for a wire-gage substantially as herein shown and described.

OBERLIN SMITH.
